UNITED STATES PATENT OFFICE.

WILLIAM GRUS, JR., OF CHICAGO, ILLINOIS.

ADJUSTABLE OILER FOR LEAF-SPRINGS.

1,280,719.

Specification of Letters Patent. Patented Oct. 8, 1918.

Application filed September 28, 1917. Serial No. 193,828.

To all whom it may concern:

Be it known that I, WILLIAM GRUS, Jr., a citizen of the United States, residing at Chicago, in the county of Cook and State of Illinois, have invented certain new and useful improvements in Adjustable Oilers for Leaf-Springs, of which the following is a specification.

This invention relates to an oiler which is applied over the top and downwardly over the sides of a portion of the edges of a leaf spring, and the principal object of the invention is to provide an adjustable oiler of this class which can be varied to accommodate springs of different widths and thicknesses.

The invention consists in the novel construction, combination and arrangement of the parts.

20 In the accompanying drawings—

Figure 1 is a side elevation of a portion of a leaf spring to which an oiler of this type is applied.

Fig. 2 is a top view of the same.

25 Fig. 3 is a sectional view taken on line 3—3 of Fig. 2.

Fig. 4 is a sectional view taken on line 4—4 of Fig. 5.

30 Fig. 5 is a sectional view taken on line 5—5 of Fig. 2.

Fig. 6 is a view looking at one end of the oiler as shown by Fig. 1.

Fig. 7 is a view of a modified form.

35 Fig. 8 is a sectional view of the modified form; and

Figs. 9 and 10 are face and sectional views of a slightly different form.

Different sized springs are used in different kinds of vehicles, particularly automobiles, to carry the loads imposed upon them in different ways. These springs may vary in width and in the number of leaves, or the thickness. To attempt to provide spring leaf oilers for all of these different sizes necessitates a great number of different sized oilers. To reduce the number of different sizes and to thereby reduce the expense of manufacture the present oiler is provided which is adjustable not only in length to accommodate springs of different thicknesses, but also in width to accommodate springs of different widths.

In the form shown by Figs. 1 to 6 there is a single sectional casing which extends across the top and downwardly over and below the sides of a portion of a leaf spring to which it is applied. This casing com-

prises sections 1 and 2 which telescope one within the other, and the outermost section 1 is formed with slots 3 in the ends, through which screws 4 extend and are inserted through the adjacent wall of the section 2, being provided with nuts 5 on the inside thereof, if necessary, so that the sections 1 and 2 may be adjusted with respect to each other and held in any adjusted position by tightening the screws 4. In the top of one of the sections is a raised portion 6, in which is a perforation 7. Pivoted at the top of the raised portion is a cap 8 with a perforation 9 which can be moved to register with the perforation 7 and with ends 10 to facilitate rotation with the cap. These sections 1 and 2 extend across the top and downwardly over the edges of the leaves 11 of a spring. Extending from the lower portions of these sections 1 and 2 are sides 12 slidable or telescoping within them. The edges of the sections 1 and 2 are formed with a plurality of notches 13 and with inwardly bent 60 tongues 14 at the ends; the sides 12 are provided with outwardly bent tongues 15 which are spaced apart to register with the notches 13. At the lower end of each side piece 12 is a bent perforated tongue 16 through 70 which a fastening bolt 17 is inserted beneath the spring to hold the oiler in place.

The sections 1 and 2 and the side extensions 12 form a housing and a substantial inclosure for a pad 18 of absorbent material, such as felt, or the like, which preferably extends in a single piece over the top and downwardly into the side portions 12, the length being varied in accordance with the size of spring to which the oiler is applied. At the top of the oiler this absorbent pad 18 is preferably formed with a slot 19 which registers with the perforation 7 in the top casing member so that the slot may act as a duct for conveying lubricant across 90 the top leaf of the portions of the pad at the sides of the leaf spring, and also acts as a reservoir for containing lubricant when the pad is sufficiently saturated. The thickness of the pad is somewhat greater than the 95 depth of the several casing portions, particularly the portions at the sides of the spring, so that when the oiler is applied to a leaf spring the pad can be, and is somewhat compressed by the tightening of the 100 bolt 17.

In operation the sides 12 are adjusted to the proper length before the oiler is applied to a spring, the tongues 15 registering and

being held by the notches 13 of the casing members 1 and 2. The width of the oiler is then adjusted by means of the screws 4, after which the oiler can be placed over the top of the leaf spring and fastened in place by the bolt 17.

The forms shown by Figs. 7 and 8, and 9 and 10, are applied only to the edge or edges of the leaves of the spring, being fastened with bolts at the top and bottom. In both of these forms there are two telescoping sections 19 and 20, one formed with overhanging portions 21 and notches 22, and the other formed with a projection 23 which engages the notches. These forms are substantially the same, with the exception that in Figs. 9 and 10 the oiling aperture 24 is made by slitting the upper section 19 at the bend of the top, forming a tongue 20 which overhangs the opening, and in the form shown by Figs. 7 and 8 a reservoir 25 is formed at the top which has a rotatable cap 26 to cover an aperture therein. In both of these forms the adjustment is made before the oilers are applied to the edges of the spring, and it will be noted that the sides of each section are inclined at top and bottom, so that the oilers will conform more nearly to the edge of the spring to which they are applied.

If desired the absorbent pad may be secured to the sectional casing by means of a staple 28, as shown in Figs. 7 and 8, or by rivets 29 in each of the two sections, as shown by Figs. 9 and 10. In the form shown by the other figures an upset rivet is secured to each of the side pieces 12. In any of these forms it is not necessary that the absorbent pad be secured to the sectional parts as there is no tendency for the pad to become dislodged when the oiler is attached to a spring.

I claim:—

1. An oiler for leaf springs having incasing parts slidable with respect to each other over the top and also on the sides of springs of different widths and thicknesses.
2. A leaf spring oiler which has telescoping casing parts extending across the top thereof and adjustable for springs of different widths.
3. A leaf spring oiler which is adjustable for springs of different thickness comprising casing parts slidable one within the other with side fastening devices for holding the parts in adjusted position.
4. A leaf spring oiler which has an adjustable top with casing parts slidable one within the other and adjustable sides for springs of different widths and thicknesses.
5. A leaf spring oiler with a casing which fits over the top and downwardly over the sides of a portion of a spring having sides adjustable in length for springs of different thickness.

6. A leaf spring oiler which fits over the top and downwardly over the sides of a portion of a spring having a sectional top which has connected parts adjustable with respect to each other for springs of different widths, and means for fastening the sections of the top together at the sides thereof.

7. In a leaf spring oiler, the combination with sections slidable one within the other and fitting over the top of a leaf spring, and side portions adjustable in the said top sections.

8. In a leaf spring oiler, a plurality of sections fitting over the top and downwardly over the sides of a leaf spring and each section adjustable with respect to the adjacent section.

9. In a leaf spring oiler, a plurality of sections forming a housing over the top and downwardly over the sides of a leaf spring and each adjustable with respect to its adjacent section, and a pad of absorbent material covered by the housing.

10. An adjustable leaf spring oiler comprising two right angled sections fitting together over the top of a leaf spring, a side section adjustable in each of the right angled sections, and means for binding the side sections together beneath a spring holding them in their adjusted positions.

11. In a leaf spring oiler, an adjustable sectional housing, which extends over the top and sides of a spring, and a pad contained therein for confining a body of lubricant against the portion of the opposite edges of the leaves of a spring.

12. In a leaf spring oiler, the combination with two right angled sections slidable one within the other, of means for holding them together, side pieces, each having adjustable connection with one of said sections, and means for holding the side pieces in adjusted position when applied to a leaf spring.

13. In a leaf spring oiler, the combination with an adjustable casing comprising a plurality of sections fitting over the top and sides of a leaf spring, one of said top sections having a covered oil aperture therein, and an absorbent pad held by the casing with a slot across the top thereof leading to the sides of a spring.

14. In an adjustable leaf spring oiler, the combination with a top casing section having notches in the edges, and a side section fitting therein having outwardly bent tongues to fit in the notches.

15. In an adjustable leaf spring oiler, the combination with a sectional casing portion having edges with notches and an inwardly turned tongue at the end, and another section with outwardly turned tongues fitting in the notches.

16. In an adjustable leaf spring oiler, the

combination with two right angled casing sections slidable one within the other and fitting over the top and downwardly over a portion of the sides of a leaf spring, of 5 means for securing these sections together, one of the sections having a covered oiling aperture, a side section for each of the said right angled sections slidable therein, an adjustable connection between said sections, 10 means for fastening the side sections together beneath a leaf spring, and a pad of absorbent material fitting over the top and downwardly over a portion of the sides of a leaf spring inclosed by said casing with a 15 slot in the top communicating with said oiling aperture and forming a duct for conveying oil to the sides of the casing and a reservoir for containing oil at the top.

17. A leaf spring oiler having a casing

comprising a plurality of telescoping sections to extend over the top and downwardly over the sides of a portion of a spring, means for adjustably attaching the sections together, a single pad of absorbent material confined by the casing, and means for attaching the ends of the pad to the end sections of the casing. 20

18. A leaf spring oiler which is composed of telescoping casing parts extending across the top and downwardly over the sides of a portion of a spring, and means at the sides of the parts for holding them in adjusted 25 positions. 30

In testimony whereof I have signed my name to this specification, on this 25th day 35 of September A. D. 1917.

WILLIAM GRUS, JR.
